[57] CLAIM

The ornamental design for a combined lavatory, soap holder and towel rack, as shown and described.

DESCRIPTION

FIG. 1 is a top front perspective view of a combined lavatory, soap holder and towel rack showing my new design;

FIG. 2 is another top front perspective view thereof;

FIG. 3 is a top plan view thereof;

FIG. 4 is a front elevational view thereof;

FIG. 5 is a right side elevational view thereof;

FIG. 6 is a left side elevational view thereof;

FIG. 7 is a rear elevational view thereof; and,

FIG. 8 is a bottom plan view thereof.

The broken line representation of a bar of soap and a towel in FIG. 2 is for purposes of illustration only and form no part of the claimed design.

*Fig. 1.**Fig. 2.**Fig. 3.**Fig. 4.*

FIG. 5.

FIG. 6.

FIG. 7.

FIG. 8.
